UNITED STATES PATENT OFFICE

LEONARD B. PAUL, OF WILLIAMSTOWN, WEST VIRGINIA, ASSIGNOR, BY DIRECT AND MESNE ASSIGNMENTS, OF ONE-THIRD TO ALICE O'MEARA PAUL, OF WILLIAMSTOWN, WEST VIRGINIA, AND TWO-THIRDS TO LOUIS G. ZACHOS, OF CHICAGO, ILLINOIS

SLIDING AND SWINGING WINDOW

Application filed August 21, 1928. Serial No. 301,065.

This invention relates to window sashes of the sliding type, and has for one of its objects to provide novel, simple and inexpensive upper and lower sashes of this character which shall be adapted to be swung into the room so as to permit them to be cleaned easily, quickly and without danger.

The invention has for a further object to provide sashes of the character stated which shall be so constructed as to permit, after raising the lower sash and lowering the upper sash, the lower sash to be swung into the room for cleaning purposes.

To attain the foregoing and other objects the invention comprehends sashes each embodying a main frame slidably arranged in the window frame, an auxiliary and glass panel carrying frame hinged to the main frame for movement with respect thereto about a vertical axis, and novel and simple means for establishing an air and water proof connection between the sides of the frame.

The invention further comprehends sashes of the character stated wherein the upper sash shall be sufficiently shorter than the lower sash to permit its auxiliary frame to be swung into the room when it is lowered and the lower sash raised.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view in elevation of a window frame and sashes constructed in accordance with my invention;

Figure 2 is a sectional view taken on the vertical plane indicated by the line 2—2 of Figure 1;

Figure 3 is a sectional view taken on the horizontal plane indicated by the line 3—3 of Figure 1;

Figure 4 is a vertical sectional view of the lower portion of the window construction with the auxiliary frame of the lower sash swung inwardly.

Figure 5 is a sectional view taken on the

horizontal plane indicated by the line 5—5 of Figure 4;

Figure 6 is a view similar to Figure 1 with the lower sash raised, the upper sash lowered and the auxiliary frame of the upper sash swung inwardly.

Figure 7 is a perspective view of a corner portion of one of the sashes.

Figure 8 is a perspective view illustrating the construction of the side members, the top and bottom members and the stop and weather strips of the sashes;

Figure 9 is a similar view illustrating the construction of the reinforced joints of the auxiliary frame members;

Figure 10 is a perspective view of the window construction with the upper sash raised, the lower sash lowered, and the auxiliary frame of the lower sash swung inwardly;

Figure 11 is an elevational view of one of the frames viewing the frame from its outer side;

Figure 12 is an elevational view of one corner of one of the auxiliary frames viewing the frame from its outer side;

Figure 13 is a perspective view illustrating the manner in which an air and water tight connection is established between the main and auxiliary frames, and

Figure 14 is a view similar to Figure 9 with the parts shown in Figure 9 arranged in assembled relation.

Referring in detail to the drawings, 1 designates a window frame which, with the exception of its top bar 2, is of well known construction. The top bar 2 is provided with vertically offset inner and outer portions 3 and 4, respectively, for a purpose which will presently appear. The lower sash 5 and upper sash 6 are slidably mounted in the window frame 1, and are connected to their counter balancing weights, not shown, by cords 7.

The sashes 5 and 6 are similar in construction, and each comprises a main frame 8 and an auxiliary frame 9, the former being slidably arranged within the window frame 1 and the latter being arranged within the former and secured thereto by hinges 10.

The main frames 8 each comprises side members 11 preferably made from wood, and

thin top and bottom members 12 and 13, respectively, made from metal. The frame members 12 and 13 are arranged in contact with the ends of the frame members 11, and are provided with angular terminals 14 which are arranged in recesses 15 formed in the frame members 11. The frame members 11, 12 and 13 are secured together by screws 16 or other suitable fastening elements which pass through the frame members 12 and 13 and their angular terminals 14 and enter the frame members 11. Metal stop and weather strips 17 are secured against the outer faces of the frame members 11 by screws 18 or other suitable fastening elements. The strips 17 extend from the lower to the upper ends of the frame members 11, and they extend laterally beyond the opposing faces of these frame members and are provided along their extended vertical edges with ribs 19 which are arranged within the main frames 8 and are of V-form in cross section. The cords 7 are secured to the frame members 12^a as at 7^a.

The auxiliary frames 9, which carry the glass panels 20, are made from wood, and the side members 21 and the top and bottom members 22 and 23, respectively, thereof are secured together by the usual mortise and tenon joints. These frames are reinforced at their corners by angle irons 14 which are recessed into the frames and secured thereto by screws 25 or other suitable fastening elements.

The auxiliary frames 9 have a snug fit in the main frames 8, and the side members 21 of the auxiliary frames are provided in their outer surfaces with angular recesses 26 for the snug reception of the extended portions and the ribs 19 of the strips 17. As the strips 17 extend across the meeting faces of the side members of the frames 8 and 9, and as the extended portions and the ribs 19 of the strips are embedded in the outer faces of the side members of the frame 9, a water and air tight connection is established between the side members of the frames.

The auxiliary frames 9 are movable into and out of position in the main frames 8 about vertical axes, the side members 11 of the main frames 8 being wide enough to permit the auxiliary frames 9 to be swung into closed or opened position without interference from the sash guiding strips of the window frame 1. The auxiliary frames 9 are held in the main frames 8 by suitable fasteners 27 which are carried by the latter for movement into and out of engagement with the former.

The upper sash 6 is shorter than the lower sash 5, and the window frame 1 has its top bar 2 provided with the vertical offset portions 3 and 4, in order to arrange the auxiliary frame 9 of the upper sash fully below the lower sash when the former is fully lowered and the latter fully raised, and thus enable

said auxiliary frame to be swung into the room for cleaning purposes.

When the sashes are fully closed, the auxiliary frame member 23 of the upper sash contacts with the outer faces and extends above and below the meeting faces of the frame members 12 and 22 of the lower sash, the horizontal guide strips 1^a and 1^b of the window frame 1 contacts with the inner and outer faces and extend across the meeting faces of the frame members 12 and 22 of the upper sash, and the inner portion of the sill 1^c of the window frame contacts with the inner faces of and extends across the meeting faces of the frame members 13 and 23 of the lower sash, all as clearly shown in Figure 2. It will thus be seen that a wind and water proof connection is provided for the horizontal frame members of the sashes as well as for the vertical frame members of the sashes. The sashes are adapted to be secured in fully closed position by a latch 28, and the lower sash is provided with a lift 29.

From the foregoing description, taken in connection with the accompanying drawings, it will be apparent that the auxiliary frame of each sash may be easily and quickly swung into the room and that the inwardly swung auxiliary frame may be cleaned in a comparatively short time, in a comparatively easy manner and without danger. It will be further understood that the main and auxiliary frames are simple, strong and durable and capable of being manufactured at a comparatively low cost. The means for establishing a water and air proof connection between the vertical members of the main and auxiliary frames are also simple, strong and durable and also capable of being manufactured and applied to the frames conveniently and at small cost.

While I have described the principle of operation of the invention, together with the device which I now consider to be the best embodiment thereof, I desire to have it understood that the device shown is merely illustrative, and that such changes may be made when desired as are within the scope of the invention and claimed.

What I claim is:

In a window construction, a sliding window sash comprising an outer frame including side rails and upper and lower metal straps bridging the upper and lower ends of the side rails having oppositely extending right angularly disposed feet imbedded in the outer faces of the rails and flush therewith, a swinging inner glass panel carrying frame received in the outer frame, hinges connecting one side of the inner frame to one side rail of the outer frame, stop strips secured to the outer side faces of the side rails and extending inwardly of the same and in the path of movement of the inner frame for limiting the swinging

movement thereof in one direction, the inner swinging frame having the outer side faces thereof provided with longitudinally extending grooves, V-shape ribs on the outer longitudinal edges of the stop strips for reception in the grooves when the swinging frame is in abutting engagement with the stop strips, and latches carried by the side rails of the outer frame for engaging the inner faces of the inner swinging frame to hold the same against movement in abutting engagement with said stop strips.

In testimony whereof I affix my signature.

LEONARD B. PAUL.
